(57) **CLAIM**

The ornamental design for a vaporizer base, as shown and described.

DESCRIPTION

FIG. 1 is a perspective view of the vaporizer base; FIG. 2 is a front elevational view of the vaporizer base of FIG. 1;

FIG. 3 is a rear elevational view of the vaporizer base of FIG. 1;

FIG. 4 is a left side elevational view of the vaporizer base of FIG. 1;

FIG. 5 is a right side elevational view of the vaporizer base of FIG. 1;

FIG. 6 is a top plan view of the vaporizer base of FIG. 1; FIG. 7 is a bottom plan view of the vaporizer base of FIG. 1;

FIG. 8 is a perspective view of a second an alternative embodiment of the vaporizer base;

FIG. 9 is a front elevational view of the vaporizer base of FIG. 8;

FIG. 10 is a rear elevational view of the vaporizer base of FIG. 8;

FIG. 11 is a left side elevational view of the vaporizer base of FIG. 8;

FIG. 12 is a right side elevational view of the vaporizer base of FIG. 8;

FIG. 13 is a top plan view of the vaporizer base of FIG. 8; and,

FIG. 14 is a bottom plan view of the vaporizer base of FIG. 8.

The broken lines in the drawings illustrate portions of the vaporizer base that form no part of the claimed design.

1 Claim, 6 Drawing Sheets
